UNITED STATES PATENT OFFICE.

ARTHUR D. MITCHELL, OF DETROIT, MICHIGAN.

HAT.

1,242,964.

Specification of Letters Patent. Patented Oct. 16, 1917.

Application filed September 1, 1915. Serial No. 48,411.

To all whom it may concern:

Be it known that I, ARTHUR D. MITCHELL, a citizen of the United States of America, residing at Detroit, in the county of Wayne, 5 and State of Michigan, have invented certain new and useful Improvements in Hats, of which the following is a specification, reference being had therein to the accompanying drawings.

10 The invention relates to the manufacture of hats and more particularly to that type in which a blank of felt, straw or other suitable material is fashioned into various shapes. It is the object of the invention to 15 facilitate the manufacture, and further to obtain a construction that is readily fashionable. To this end the invention comprises the novel method and construction as hereinafter set forth.

20 In the drawings:

Figure 1 is a perspective view of a hat embodying my invention;

Fig. 2 illustrates the process;

Fig. 3 is an enlarged cross section through 25 the rim;

Fig. 4 is an elevation thereof;

Fig. 5 is a section showing the manner of securing the ends of the reinforcing wire; and

30 Fig. 6 is a cross section thereof.

A is the blank from which the hat is formed and which is of any suitable material, such as soft felt. B is the rim portion, which is fashioned to the desired contour and which is faced with suitable material C, such as velvet. To simplify the process of manufacture and also to facilitate the fashioning and re-fashioning of the hat, the method of construction is as follows: The 35 blank A is first placed on a suitable block D, and a portion of the rim to be faced is coated with water-proof adhesive material, preferably liquid rubber cement. The fac-

ing material C is also preferably coated on its inner face with the cement. A fashionable reinforcing wire E is then placed around the rim, preferably parallel with the edge thereof, but spaced a short distance therefrom. This wire has a fabric coating F which will adhere to the cement coated 45 face of the rim and the facing material covering the same. The opposite ends of the wire may be secured to each other by a suitable coupling sleeve G, after which the facing material C is placed over the rim and 50 pressed into contact therewith, as shown in Fig. 2.

In the steps thus far described, the final form of the hat is not imparted thereto, but on the contrary, the rim may be left in circular form, which facilitates the attachment of the reinforcing wire and the facing material. As soon, however, as the cement has 55 set, the rim may be fashioned to any desired contour by merely bending the wire. 60 Thus the necessity of re-blocking is dispensed with and at any time the form of hat may be easily changed.

In addition to its function of imparting 65 form to the hat the wire E forms a bead 70 parallel to the edge, which adds to the appearance.

What I claim as my invention is:—

In a hat, the combination with the rim portion formed of sheet material, of a fashionable reinforcing wire placed about said rim adjacent the edge and a facing cemented to said rim covering and securing said reinforcing wire, whereby the shape of the 75 rim portion of the hat may be varied. 80

In testimony whereof I affix my signature in presence of two witnesses.

ARTHUR D. MITCHELL.

Witnesses:

NATHANIEL RETTENMIER,
THOMAS A. CRAWFORD.
